(57) CLAIM

The ornamental design for a toilet paper shield, as shown and described.

DESCRIPTION

FIG. 1 is a perspective view of the toilet paper shield in use with a toilet paper roll holder.

FIG. 2 is a front-left perspective view of the toilet paper shield;

FIG. 3 is a front view thereof;

FIG. 4 is a back view thereof;

FIG. 5 is a top view thereof

FIG. 6 is a bottom view thereof; and,

FIG. 7 is a side view thereof.

Those portions of the figures that are presented in broken lines merely illustrate the environment of the design and are not part of the claimed design.
